UNITED STATES PATENT OFFICE.

ADOLPH LUNDGREN, OF CHICAGO, ILLINOIS, ASSIGNOR OF ONE-THIRD TO RALPH A. LUNDGREN, OF CHICAGO, ILLINOIS.

CASEMENT-WINDOW SCREEN WITH OPERATING MECHANISM.

Application filed September 15, 1924. Serial No. 737,638.

To all whom it may concern:

Be it known that I, ADOLPH LUNDGREN, a citizen of the United States, and a resident of the city of Chicago, county of Cook, and

5 State of Illinois, have invented certain new and useful Improvements in Casement-Window Screens with Operating Mechanism, of which the following is a specification.

10 My invention relates to a new and useful casement window screen with operating mechanism, and the main object of the invention is to provide such a screen with means or mechanism for conveniently operating the screen positioned at the inner side 15 of the casement window.

Other objects will appear hereinafter.

The invention consists in the combinations and arrangements of parts hereinafter described and claimed.

20 The invention will be best understood by reference to the accompanying drawings forming a part of this specification, and in which,

25 Fig. 1 is an elevational view of my invention applied to a casement window,

Fig. 2 is an enlarged vertical section taken on line 2—2 of Fig. 1,

Fig. 3 is a cross section taken on the line 3—3 of Fig. 2,

30 Fig. 4 is an enlarged vertical section taken on line 4—4 of Fig. 1,

Fig. 5 is an enlarged horizontal section taken on line 5—5 of Fig. 1,

35 Fig. 6 is a vertical sectional view taken through the operating means, when the screen is unrolled,

Fig. 7 is a horizontal sectional view showing a modified form of operating means, and

40 Figs. 8 and 9 are vertical sectional views taken respectively on lines 8—8 and 9—9 of Fig. 7.

My invention is especially adapted for use with a casement window, and in the drawings I have shown a window frame 10 with an outwardly opening pair of casement windows 11. The roller 12 with the screen 13 thereon is mounted within the upper part of the window frame, out of view, and slots 14 are provided in the sides of the frame for the side edges of the screen to travel through. A sheave 15 with a guard flange 16 is fastened with screws or any suitable means to each end of roller 12 and preferably has a friction ring 17 of leather or

50 the like fastened around its exterior. A pin

18 extends through said sheave into the roller and is journaled in a bracket 19 which is secured into the window frame for rotatably mounting said roller.

The operating mechanism or means, in the preferred form illustrated in Figs. 1 to 6, comprises an operating member 20 secured to a shaft 21 and rotatably mounted therewith in plates or side members 22 removably mounted in the posts 23 of a bracket 24 which is secured with screws or the like to the lower member or base plate 25 of the window frame 10, as shown in Fig. 6. A crank or member 26 is provided for manually operating shaft 21 and member 20, and is connected to said shaft with a pivot pin 27 so as to be swung laterally against the window frame and underneath the front part of base plate 25 (see Figs. 1 and 6) so as to be placed entirely out of the way.

The member 20 is constructed or provided with an annular flanged portion or sheave 28, preferably formed integral therewith, around which is looped an endless flexible member or cable 29 which extends in opposite directions from the said member and over guide pulleys 30 mounted on shafts 31 placed within the lower corners of frame 10, beneath base plate 25, and said cable passes up over the sheaves 15 on roller 12 and down again over pulleys 32 on said shafts 31, and extends beneath member 20. This endless cable actuated by said annular portion or sheave 28 provides means for engaging the sheaves or means 15 on the ends of the roller and for positively operating said roller to roll up the screen. The member 20 is also provided with spirally grooved means 33 which is preferably in the form of a conical portion with a pair of spiral grooves on its exterior extending from said sheave 28 to the opposite larger end of operating member 20; and a pair of flexible members or cables 34 are fastened each with one end 35 in openings at opposite points of said larger end, and extend over pulleys 36 mounted on said shafts 31 and are connected to the outer edge or corners of screen 13, preferably adjacent the ends of a re-enforcing strip 37 provided on the free edge of said screen.

The sheave 28 and the spirally grooved conical portion 33 are so arranged in diameter as to properly compare with the diameter of sheaves 15 on roller 12 and with the varying diameter of the unrolling and

the rolling screen, that said screen is rolled and unrolled by means of said sheave 28 and conical portion 35 so that said cables 29 and 34 will always be operated at an equal tension and without producing any slack in either one of them; this may be readily effected by making the sheave 28 equal in diameter with the sheave 15, and making the larger end of the spirally grooved portion 33 equal in diameter with the diameter of the screen when rolled upon the roller, and by making the smaller end of the spirally grooved portion 33 equal in diameter with the roller 12 or the inner part of the screen 13 when substantially entirely unrolled. This is apparent when it is noted that the lower end of cable 34 is attached to the outer end of the groove portion 33, as best seen in Fig. 5, while the other end of said cable 34 is attached to the outer end of screen 13 and is located at the upper end of the window frame when said screen is rolled up, and as the screen is then unrolled from its larger diameter while the cable 34 is pulled downward, the lower end of this cable is winding around the larger end of conical portion 33, and thus continues being wound toward the smaller end of said conical portion 33 in exact ratio with the decreasing diameter of the screen as it is being unwound, and each rotation of shaft 21 with portions 33 and 28 will thus produce the proper amount of travel and tension upon the cables 34 and 29 respectively for operating the screen.

In the modified form shown in Figs. 7, 8, and 9, the same construction of bracket means 22, 23 and 24 may be used and mounted in the lower part of the window frame 40, and also the same shaft 21 with crank 26, and the pulleys 30, 32 and 36, and cables 29 and 34, may be used as in the preceding form; but in place of the above described single conical member 20 with two spiral grooves thereon, two conical members 40 are used each having a single spiral groove 41 on its exterior and a gear 42 at its smaller end, each member 40 being rotatably mounted with an axle 43 placed in additional openings provided in the plates 22, adjacent the openings in which shaft 21 is mounted; and a gear 44 with an integral member or sheave 45 is secured on shaft 21 and engages said gears 42 to operate them in unison in the same direction. The endless cable 29 is looped over said sheave 45 in the same manner as over sheave 28 in the preceding form, and the lower or free ends 35 of cables 34 are each fastened to the larger end of one of the members 40, each being wound in the single spiral groove 41 during the unwinding of the screen 37, instead of both of said cables 34 being wound in the double grooves 33 provided on member 20 in the preceding form. The result and operation

of this form of mechanism is the same as in the preceding form.

The plates 22 are preferably arranged to be adjustable, as by use of screws 46 extending down through the window stool 70 or plate 25 and engaging in threads 47 in said plates 22 to adjust and retain said plates vertically, the heads 48 of said screws being held in position between the material of the window plate or stool and a plate 49 seated in the top of said window plate or stool and fastened in position thereon with suitable screws or the like.

The above described mechanism in either of its forms, thus provides means for positively rolling or unrolling the screen, and is conveniently operated by means of the crank 26 which is readily foldable against the window frame and out of the way, and no springs of any kind are used or needed 85 for either rolling or unrolling the screen as is necessary in the usual construction.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations 95 and modifications as come within the scope of the appended claims:

1. A device of the class described comprising a roller with a screen thereon, sheaves secured to the ends of said roller, 100 flexible means engaging over said sheaves, flexible means connected to the end of said screen, and a member engaging all of said flexible means and including a conical portion for actuating one of said flexible means 105 to keep equal tension on all of them during operation of said screen.

2. A device comprising a roller and a screen thereon, flexible means engaging means on said roller for positively actuating said screen, flexible means attached to said screen for unrolling the same, and a rotary member mounted apart from said roller and screen for engaging both flexible means and having a conical portion for engaging and operating one of said flexible means so as to be at equal tension with the other flexible means.

3. A roller with a screen arranged to be mounted in a window frame, flexible means for operating said roller to roll said screen, flexible means attached to said screen for unrolling the same, and a member having means for engaging and actuating one of said flexible means at a constant rate of 120 travel and having a portion with spirally arranged means for receiving and operating the other of said flexible means at a varying rate of travel.

4. A roller with a screen arranged for 130

- mounting it in a window frame, means for operating said roller to roll up said screen, means for drawing and unrolling said screen, and a rotatable member with an annular portion for operating said roller operating means and with a conical portion for operating said screen drawing means.
5. A roller with a screen and with flanged means at its ends, flexible means engaging over said flanged means, flexible means attached to said screen, and a rotatable member with an annular portion for engaging and operating the first said flexible means and with a spirally grooved portion for engaging and operating the second said flexible means.
6. Mechanism for operating a roller with a screen thereon, and comprising a rotatable operating member with spiral means thereon, an endless flexible member looped around a portion of said operating member for travelling over means on said roller to actuate same, and a flexible member attached to the outer end of said screen and arranged to be wound on the spiral means of said operating member.
7. Mechanism for operating a roller with a screen thereon, and comprising a rotatable operating member with an annular portion and a spirally grooved portion, an endless cable looped around said annular portion and engageable over means on said roller, and a cable attachable to the outer end of said screen and to said operating member and being windable on said spirally grooved portion to operate said cable at equal tension with said endless cable.
8. Mechanism for operating a roller with a screen thereon, and comprising a rotatable operating member with an annular portion and with a double spirally grooved portion, an endless cable looped around said annular portion and engageable over means on each end of said roller for rolling up said screen, and a pair of cables attachable to the outer corners of said screen and windable on said double spirally grooved portion for operating said cables at equal tension with said endless cable.
9. Mechanism for operating a roller with a screen thereon, and comprising sheaves fastened to the ends of said roller, a rotatable operating member with an annular portion and a conical portion, an endless cable looped around said annular portion and engageable over said sheaves, and a cable attachable to the outer end of said screen and windable on said conical portion.
10. The combination in a window frame, of a roller with a screen thereon and with means at its ends for rotatably mounting it in said frame, an operating member mounted within said frame, an endless flexible member passing over said means on said roller and over means on said operating
- member, and flexible means attachable to said screen and to a conical portion on said operating member to be wound thereon.
11. The combination in a casement window frame, of a roller with a screen thereon and with sheaves secured to its ends and having means for rotatably mounting it concealed within said window frame, an operating member mounted within said frame, an operating crank connected thereto and foldable against said frame, an endless cable passing over said sheaves and looped over a portion on said operating member, flexible means attached to the corners of said screen and to spiral means on said operating member to be wound thereon, and pulleys for guiding said cables.
12. The combination in a window frame, of a roller with a screen thereon and with sheaves secured to its ends and means for rotatably mounting said roller concealed within the upper part of said frame, an operating member with bracket means for rotatably mounting it concealed within the lower part of said frame, an endless flexible member passing over said sheaves and looped around a portion of said operating member, and flexible means attached to the outer end of said screen and windable on a conical portion of said operating member.
13. Mechanism for operating a roller with a screen thereon, and comprising a pair of rotatable members with means for mounting them in a window frame, means for rotating said members in unison and having a sheave thereon, cable means looped over said sheave and engageable over means on said roller, and cable means attached to each rotatable member and to the outer edge of said screen.
14. Mechanism for operating a roller with a screen thereon, and comprising a pair of rotatable members with spiral grooves thereon, a sheave with gear means for rotating said members in unison, an endless cable looped over said sheave and engageable over means on the ends of said roller for actuating same, and cable means attached to each rotatable member and to the outer edge of said screen for unrolling the screen.
15. Mechanism for operating a roller with a screen thereon, and comprising a bracket with a pair of spirally grooved members rotatably mounted therein, a gear on each member, a sheave with a gear engaging said gears and rotatably mounted with a shaft in said bracket, and manual means for operating said shaft and thereby said rotatable means.
16. Mechanism for operating a roller with a screen thereon, and comprising a bracket with a shaft carrying a conical member having a pair of spiral grooves thereon and having a sheave at its smaller

end, and a crank foldably connected to said shaft for operating said member.

17. Mechanism for operating a roller with a screen thereon, said mechanism comprising a bracket mountable on the lower side of a window stool or plate, plate means movably mounted in said bracket, a spirally grooved conical member mounted with a shaft in said plate means, threaded means 10 for adjusting said plate means with said

conical member vertically in said bracket, and means for rotating said conical member.

In testimony whereof I have signed my name to this specification in the presence 15 of two subscribing witnesses.

ADOLPH LUNDGREN.
